DESIGN FOR A HAIR WAVING DEVICE

Virginia S. Graham, Beverly Hills, Calif.

Application July 10, 1946, Serial No. 131,443

Term of patent 14 years

(Cl. D86—10)

To all whom it may concern:

Be it known that I, Virginia S. Graham, a citizen of the United States, resident of Beverly Hills, Los Angeles County, California, have invented a new, original, and ornamental Design for a Hair Waving Device, of which the following is a specification, reference being had to the accompanying drawing, forming part thereof.

Referring to the drawing:

Figure 1 is a perspective view of a hair waving device, in open position showing my new design;

Figure 2 is a top plan view of the hair waving device of Figure 1 with the upper section in closed latched position;

Figure 3 is a side elevational view of the hair waving device as shown in Figure 2; and

Figure 4 is an end elevation as viewed from the right of Figure 2.

I claim:

The ornamental design for a hair waving device, as shown.

VIRGINIA S. GRAHAM.
